UNITED STATES PATENT OFFICE.

ARTHUR ZADEK, OF NEW YORK, N. Y.

DISPLAY DEVICE.

Application filed June 23, 1925. Serial No. 38,967.

To all whom it may concern:

Be it known that I, ARTHUR ZADEK, citizen of the United States of America, residing in the city, county, and State of New York, have invented new and useful Improvements in a Display Device, of which the following is a specification.

My invention relates generally to display devices and has reference to a device of this 10 character particularly adapted for displaying small toys and other articles, such as children's rattles which can be readily suspended from the device in display position.

This invention comprises a suitable base 15 member supporting an upright upon which are mounted, at different elevations, continuous supporting racks of springy material provided with separably attached ends over which the articles to be displayed can 20 be inserted and removed by disengaging the connection.

The object of the invention is to provide a display of this character which is durable in construction and attractive in appearance, 25 and which affords facilities whereby any selected article on the racks may be removed without removing any of the other articles displayed on the same rack.

A further object of this invention is to 30 provide a rack made of one piece of material which is formed with an annular portion and a radial spoke and hub to receive the upright of the supporting base.

The invention is illustratively exemplified 35 in the accompanying drawing, in which, Figure 1 is a perspective view of my improved display device showing several articles suspended therefrom; Figure 2 is a plan view of one of the supporting racks; 40 and Figure 3 is a perspective view of the separable fastening means for the ends of the rack.

Referring to the drawings, 10 denotes a base plate preferably round in plan and 45 conical in cross section. The center of the base is provided with a boss having a threaded bore to receive an upright member in the form of a rod 11 of sufficient height to accommodate preferably two spaced superposed supporting racks 12, each thereof comprising a single strip of springy metal. The strip of metal is folded together at its mid portion forming two parallel portions into a straight radial spoke 13, the material at 50 the inner end thereof being separated and bent to form a loop 14. The two strands

of the strip beyond the spoke 13 are curved towards each other to describe an annular rack or hoop 15. Suitable separable fastening means 16 is provided at the ends of the curved strands so as to enable the ends to be readily released and the toys removed when desired.

The hoop portion 14 embraces a hub 17, 60 which is provided with a bore to receive the rod 11 and a set screw 18 to be adjusted against the rod 11, and which may be set at any elevation to support the suspended toys 19. Preferably the lowermost rack 12 is 65 the larger, while the upper rack is the smaller and may be rigidly attached to the upper end of the rod, as illustrated.

From the foregoing it will be clear that, 70 when the display is assembled and the rattles disposed in suspended position on the racks 12, as illustrated in Figure 1, any rattle selected by a customer may be removed from the display stand by simply moving the other rattles along the curved portions of the rack until the selected toy is adjacent the separable ends of the rack, which are 75 then released and the article removed.

The present invention has a decided advantage over the types now in use for this 80 purpose, which ordinarily include merely 85 arcuate rods supported on braces and having their ends upturned to prevent accidental removal of the articles supported on the rods, because the closed racks 12 of my device prevent removal of the articles under 90 any circumstances unless the ends are purposely separated. This provision does not interfere with the display purpose of the device and in addition enables any toy to 95 be removed without removing any other toy on the same rack, and further prevents a dishonest person from removing an article from the rack without deliberately disengaging the ends thereof.

What I claim is:

1. In a display device of the character described, the combination of a base member, an upright therefor, and adjustable rack for the upright, comprising a single piece of springy metal strip bent at its mid portion to form parallel portions having a loop at the inner end to embrace the upright and opposite curved portions adapted to be brought together at their ends to form an 100 annular portion, and separable fastening means for the ends of said curved portions.

2. In a display device of the character

described, the combination of a base member, an upright rod projecting from the base, and a plurality of spaced racks for the rod, each thereof comprising a single piece of springy material bent at the mid portion to form parallel adjacent spoke portions terminating at the end in a loop and having the portions beyond the spoke curved

and adapted to be brought together to form a continuous portion, means for separably attaching the ends of the curved portions together, and a hub to engage the rod and to be embraced by the loop portion of the spoke.

In testimony whereof I affix my signature.

ARTHUR ZADEK.
